GAME DEVICE

Henry F. Ahrens, Richmond Hill, N. Y.

Application October 19, 1938, Serial No. 235,867

5 Claims. (Cl. 273—118)

My invention relates to amusement devices, and has among its objects and advantages the provision of an improved game of skill.

An object of my invention is to provide a game of skill including a field upon which free rolling balls are successively discharged and deflected in various directions through the medium of mechanical devices beyond the control of the player and in which novel manually actuated traps are incorporated for trapping balls for score registering purposes. The playing field comprises an inclined surface characterized by a plurality of mechanically rotated areas or deflectors for deflecting or propelling the balls in accidental directions. The areas or deflectors comprise continuations of the playing field and are so related as to require the delivered balls to roll into contact with at least a number of the areas.

The traps are distributed over the playing field and are electrically related to lamps in a scoring device for illuminating the score. The traps are in the nature of cups normally lying underneath the playing field in combination with manually actuated linkages for selectively bringing the cups above the surface of the playing field for trapping the balls and thereby registering scores.

In the accompanying drawings:

Figure 1 is a top plan view of a game device in accordance with my invention;

Figure 2 is a longitudinal sectional view;

Figure 3 is a transverse sectional view;

Figure 4 is an enlarged sectional view of one of the traps;

Figure 5 is a view similar to Figure 4, but illustrating the trap in its normal position; and

Figure 6 is a diagrammatic view of the electric circuit associated with the scoring mechanism.

In the embodiment selected to illustrate my invention, I make use of a housing 10 of box-like formation. The housing includes a bottom 12, end walls 14 and 16, and side walls 18. The upper margins of the side and end walls carry a frame 20 for supporting a closure 22, which may comprise glass. Inside the housing 10, beneath the closure 22, I mount an inclined playing field 24, which is mounted on supports 26 glued or otherwise secured to the side walls 18. End wall 16 is extended at 28 to provide a housing 30 which contains a plurality of lamps 32 for illuminating the registered scores. Playing field 24 declines in the direction of the end wall 14, so that free rolling balls delivered to the playing field through the medium of a runway 34 will gravitate toward the end wall 14.

Playing field 24 is characterized by a plurality

of rotary discs or areas 36, 38 and 40. The discs are centrally aligned longitudinally of the field 24 and comprise continuations of the playing field, since their upper surfaces terminate flush with the upper surface of the field. Field 24 also includes a plurality of rotary discs or areas 42, 44, 46 and 48 located between the discs 36, 38 and 40 and the side walls 18. Discs 42, 44, 46 and 48 similarly comprise continuations of the playing field, in that their upper faces terminate flush with the upper face of the field 24. Fig. 2 illustrates the field 24 as being recessed at 50 for housing the individual discs to bring their upper surfaces flush with the field 24.

Disc 36 includes curved ball deflecting grooves 52 radiating radially of the disc from the axis thereof. Discs 38 and 40 are plane, but of the same diameter as the disc 36. Each of the discs 42, 44, 46 and 48 is provided with four upstanding and right-angularly related flanges 54. The flanges 54 are positioned radially of their respective discs and are preferably spaced ninety degrees apart, as illustrated in Fig. 1. This view illustrates the flanges 54 as extending slightly beyond the perimeters of their respective discs.

I mount a motor 56 on the bottom 12, which motor drives a pinion 58 arranged in mesh with a bevel gear 60. Bevel gear 60 is keyed to a shaft 62 having its lower end rotatably journaled at 64 in a frame 66. To the upper end of the shaft 62 I key a gear 68. A frame 70 is positioned between the hub of the gear 68 and the field 24 for rotatably supporting the upper end of the shaft 62, while the shaft extends through an opening in the field 24 and is fixedly connected with the disc 38.

Gear 68 is arranged in mesh with a gear 72 meshing with a gear 74 which rotates the disc 48. Gears 72 and 74 are keyed to shafts 76 and 78, respectively, journaled in the frames 66 and 70 in the same manner as the shaft 62. Gear 74 meshes with a gear 80 which meshes with a gear 82 keyed to the shaft 84 of the disc 36 for rotating the latter. The shaft 86 associated with the gear 80 is rotatably journaled in the frames 66 and 70, which is also true of the shaft 84. Gear 82 is arranged in mesh with a gear 88, which in turn is arranged in mesh with a gear 90 for rotating the disc 42. Shafts 92 and 94 associated with the gears 88 and 90, respectively, are journaled in the frames 66 and 70. A second gear 96 is arranged in mesh with the gear 68 and is in mesh with a gear 98 for driving the disc 46. Gears 96 and 98 are keyed to shafts 100 and 102.

102, respectively, journaled in the frames 66 and 70.

Gear 98 is in mesh with a gear 104 arranged in mesh with a gear 106 for driving the disc 40. Shafts 108 and 110 associated with the gears 104 and 106, respectively, are journaled in the frames 66 and 70. Gear 106 is arranged in mesh with a gear 112 which is arranged in mesh with a gear 114 for driving the disc 44. Shafts 116 and 118 associated with the gears 112 and 114, respectively, are also journaled in the frames 66 and 70. It will thus be seen that operation of the motor 56 will impart rotation to all the discs incorporated in the playing field 24.

15 Motor 56 is electrically connected with a time switch 120 which may be provided with a coin slide 122 operable upon insertion of a coin of predetermined denomination for closing the circuit to the motor for a given period of time. Such

20 switches are old and well known in the art and need not be described in further detail. Playing field 24, adjacent the end wall 14, terminates in a trough 123 which extends the full width of the playing field and declines in the direction of a conduit 124 extending along one of the side walls 18 and to a position centrally of the housing 10 adjacent the end wall 16. Conduit 124 declines in the direction of the end wall 16 so that balls delivered thereto will gravitate into receiving relation with a ball delivery device 126.

25 Delivery device 126 comprises a circular disc 128 provided with spaced fins 130 projecting radially from its peripheral face 132. Fins 130 are spaced to receive the balls 134, and the disc 128 rotates inside a housing 136 having close fitting relation with the fins for conveying the balls upwardly into delivery relation with the runway 34. The balls 134 roll into position between the fins 130 from the discharge end of the conduit 124.

30 Peripheral face 132 is angular so that the balls 134 will gravitate into the runway 34 as they are brought into alignment therewith.

35 Disc 128 is keyed to a shaft 138 connected with a bevel gear 140 arranged in mesh with a bevel gear 142 keyed to the shaft 84. It will thus be seen that the disc 128 is driven through the medium of the motor 56. Balls 134 discharged onto the playing field 24 will tend to gravitate in the direction of the end wall 14. Discs 36 to 48, inclusive, rotate at a sufficiently rapid speed to cause the balls to be deflected or propelled in irregular or tortuous paths so that no two balls will travel the same path. Balls coming in contact with the flanges 54 are projected vigorously 40 in different directions, and a given ball may be brought into contact with a number of the discs in its course over the playing field 24. Eventually the balls will complete their courses and drop into the trough 123, after which the conduit 124 will carry the balls into pickup relation with the ball delivery device 126.

45 Means is provided for arresting or trapping balls during their irregular courses over the playing field 24. Such means is manually actuated and is designed to register the score of a given player.

50 Fig. 1 illustrates a plurality of traps 144, 146, 148, 150, 152 and 154. Normally the traps lie underneath the playing field 24, but may be brought into positions above the playing field for trapping balls and recording scores. According to Fig. 1, the discs 42 and 44 are alternately positioned between the traps 144, 146 and 148. Similarly, the discs 46 and 48 are alternately positioned between the traps 150, 152 and 154. The

traps are identical in construction so that the description of one will refer to all. Figs. 4 and 5 best illustrate the construction and operation of the traps. Fig. 5 illustrates the normal position of the trap 144 illustrated therein.

5 The basket or cup 156 has its peripheral margin reinforced by a circular ring 158. Ring 158 includes arms 160 fixedly related to a shaft 162 rotatably carried by bearings 164 anchored to the playing field 24. Playing field 24 is provided with a curved slot 166 of sufficient proportions to permit the cup 156 to be pivoted therethrough about the axis of the shaft 162 to the position of Fig. 4. Fig. 4 illustrates the ball 134 trapped in the cup 156. Shaft 162 is fixedly connected with a 15 crank arm 168 pivotally connected at 170 with a link 172 pivotally connected at 174 with a rod 176 rotatably carried by a bracket 178 and the end wall 14.

20 Rod 176 extends through the end wall 14 for connection with a grip 180 which is manually rotated for imparting rotary motion to the shaft 176. Rotation of the shaft 176 actuates the link 172, which in turn imparts rotary motion to the shaft 162 for moving the cup 156 from the position of Fig. 5 to that of Fig. 4 for trapping the ball 134. Similarly, the operating linkage is manually manipulated for moving the cup 156 from the position of Fig. 4 to that of Fig. 5 for releasing the ball 134 and returning the cup to its 30 normal position. In its normal position, the cup 156 lies in the clear of the upper surface of the playing field 24 so as not to obstruct the balls rolling thereon. Trapping of the balls 134 simultaneously illuminates and records the score 35 value of the particular cup which has been successfully manipulated for trapping one of the balls.

25 Housing 30 is provided with partitions 182 to provide compartments 184 each of which includes 40 one of the lamps 32. The wall 186 of the housing 30 is provided with a series of openings 188 which register with the lamps 32 located in the compartment 184. Across each opening 188 extends a transparent sheet 190 which is made secure by 45 a retaining ring 192 screwed to the wall 186. Fig. 3 illustrates the sheets 190 as being provided with numerals 194 of different values. One lamp 32 is provided for each of the traps 144 to 154, inclusive. Thus each trap is characterized by a 50 score value and no two values are alike. The score is recorded only when one of the balls 134 has been trapped according to Fig. 4. Such trapping of the ball closes the circuit through the lamp associated with that particular trap for 55 illuminating the score.

60 Referring to Figs. 4 and 5, the playing field 24 is provided with a relatively large opening 196 across which I mount a plate 198 of insulating material. Playing field 24 is recessed on its bottom face about the opening 196 for accommodating the plate 198. The upper face of the playing field 24 is recessed for accommodating a ring 200 having an inside diameter somewhat smaller than the diameter of the opening 196 so as to have 65 restraining relation with a switch plate 202 slideable inside the opening 196. To the plate 198 I secure one end of a spring contact strip 204 by a screw or bolt 206 to which a wire 208 is electrically connected.

70 Strip 204 is provided with a contact point 210 arranged to be brought into circuit closing relation with a contact 212 anchored to the plate 198 by a bolt 214. Bolt 214 is electrically connected with the wire 216. The circuit through the lamp 75

32 associated with the cup 156 is closed when the point 210 is moved into contacting relation with the point 212. Cup 156 is of such depth as to exert pressure on the ball 134 for depressing the plate 202 and bringing the point 210 into circuit closing relation with the point 212, see Fig. 4. The balls 134 comprise resilient solid rubber. Bolts 218 fixedly relate the plate 198 and the ring 200 to the field 24. All the switch devices associated with the traps 144 to 154, inclusive, are identical so that the description directed to Figs. 4 and 5 will include all the traps.

Fig. 6 illustrates the electric circuit associated with the traps and the score recording mechanism. The time switch 120 is connected with the line wires 220, while the switch is connected with the motor 56 through the medium of wires 222. The primary coil 224 of a step-down transformer 226 is connected with the wire 222 through the medium of wires 228. The low tension coil 230 of the transformer is connected with wires 232 and 234. Wire 232 is connected with the lamps 32, while the wire 234 is connected with the contacts 212 of the traps 150, 152 and 154 through the medium of the wires 216.

A wire 236 is connected with the wire 234 and is electrically connected with the contacts 212 of the traps 148, 144 and 146 through the medium of the wires 216. Contacts 206 of all the traps are electrically connected with the lamps 32 through the medium of wires 238. It will thus be seen that trapping of a ball 134 by any one of the traps will close the circuit through the lamp 32 associated with that trap, since the lamps and their respective switches are connected in parallel in the lamp circuit.

In operation, motor 56 will operate for a period of time, during which time the balls 134 will be successively dropped upon the playing field 24. The balls entering the playing field will be deflected or propelled in irregular courses quite rapidly. The traps are manually actuated, while the balls are mechanically propelled so as to be beyond the control of the player. However, balls coming within the range of the traps may be caught in the cups 156 for registering scores. The traps are individually manipulated so that both hands may be employed.

The irregular courses of the balls over the playing field necessitates considerable skill on the part of the player for trapping purposes. Trapped balls immediately illuminate the registering mechanism associated with the trapped balls. After trapping, the balls may be released by moving the cups 156 to their normal positions, after which the balls will again be brought into play on the field 24 until such time as they gravitate downwardly beyond the range of the rotary discs and drop into the trough 123.

The balls are delivered successively onto the playing field 24. A predetermined number of balls may be provided. The successive delivery of the balls in combination with the rotary discs will cause a number of balls to be simultaneously active on the field at a given time, thus necessitating additional skill on the part of the player. The discs are so arranged as to require the balls to come in contact with a number of the discs as they tend to gravitate downwardly of the field. Discs 42, 44, 46 and 48 are closely situated to the side walls 18 so as to prevent the balls from escaping these discs during any travel of the balls along the side walls.

In Figure 1, I illustrate the shafts 176 as being provided with springs 240 cooperable on the

shafts 176 and the end wall 14 for returning the traps to their normal positions underneath the field. Traps 144 to 154 may be provided with identifying numerals or indicia 242, which indicia is duplicated on the grips 180 for definitely indicating the respective traps operatively connected with the grips.

I claim:

1. A game of skill comprising a housing having an inclined field provided with ball collecting means at its lower end, ball elevating means located at the opposite end of the field for delivering balls onto the field, a gravity conveyer for moving the balls from the ball collecting means to the ball elevating means, a motor for operating the ball elevating means, a plurality of ball deflecting devices on the field, operating connections between the motor and the ball deflecting means, and manually actuated ball traps distributed over the field and being operably accessible from positions exteriorly of the housing.

2. A game of skill comprising a field inclined to gravitate a ball downwardly of the field, rotative ball deflectors distributed over the field for deflecting the ball in an irregular course, means for rotating the deflectors, pressure responsive scoring switches distributed over the field, said field being provided with an opening adjacent each of said switches, and a manually actuated ball trap for each switch normally located underneath said field and being adapted to be projected through its respective opening in the field for trapping the ball and holding the latter against its respective switch for closing the latter.

3. A game of skill comprising an inclined field provided with ball collecting means at its lower end, ball elevating means located at the opposite end of the field for delivering balls onto the field, an inclined runway for moving the balls from the ball collecting means to the ball elevating means, rotative ball deflectors distributed over the field for deflecting the balls in irregular courses, a motor having operating connections with the deflectors for rotating the latter and an operating connection with said ball elevating means, pressure responsive scoring switches distributed over the field, and a manually actuated ball trap for each switch for trapping one of said balls and holding the trapped ball against its respective switch for closing the same.

4. A game of skill comprising an inclined field provided with ball collecting means at its lower end, ball elevating means located at the opposite end of the field for delivering balls onto the field, an inclined runway for moving the balls from the ball collecting means to the ball elevating means, rotative ball deflectors distributed over the field for deflecting the balls in irregular courses, a motor having operating connections with the deflectors for rotating the latter and an operating connection with said ball elevating means, pressure responsive scoring switches distributed over the field and having pressure plates lying flush with the upper face of the field and movable in openings in the field, said field being provided with slots, and manually actuated ball traps normally lying underneath the field and adapted to be projected through the slots for trapping balls on the field and holding the latter against their respective pressure plates for closing the switches.

5. A game of skill comprising an inclined field provided with ball collecting means at its lower end, ball elevating means located at the opposite end of the field for delivering balls onto the field, an inclined runway for moving balls from the ball

collecting means to the ball elevating means, rotative ball deflectors distributed over the field for deflecting the balls in irregular courses over the field, a motor having operating connections with said deflectors for rotating the latter and an operating connection with said ball elevating means, said field being provided with a plurality of slots

distributed over the field, and manually actuated ball scoring traps normally lying underneath the field and adapted to be selectively projected through their respective slots for trapping balls deflected within range thereof. 5

HENRY F. AHRENS.
